UNITED STATES PATENT OFFICE.

WILLIAM P. PITT, OF INDEPENDENCE, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

1,088,176.

Specification of Letters Patent.

Patented Feb. 24, 1914.

Application filed November 8, 1911. Serial No. 659,143.

To all whom it may concern:

Be it known that I, WILLIAM P. PITT, a citizen of the United States, residing in Independence, in the county of Jackson and 5 State of Missouri, have invented certain new and useful Improvements in Loose-Leaf Binders, of which the following is a specification.

My invention relates to improvements in 10 loose leaf binders.

It relates particularly to the type of loose 15 leaf binders in which a clamping member, to which is hinged a cover, is adapted to be adjustably mounted on parallel supporting 20 posts.

One object of my invention is to provide a cheaply made, strong and efficient hinge mechanism for connecting the cover to the clamping member.

25 A further object of my invention is to provide a tubular clamping member with novel means for preventing the ends of the clamping member cutting through the material with which the clamping member may be bound.

Other novel features of my invention are hereinafter fully described and claimed.

In the accompanying drawings which illustrate the preferred form of my invention, 30 Figure 1 is a plan view of my improved clamping member shown attached to a cover, a portion of which is broken away. Fig. 2 is a side elevation of the clamping member. Fig. 3 is a cross section on the line *a—b* of 35 Fig. 1. Fig. 4 is a perspective view of one end of the body of the clamping member. Fig. 5 is a perspective view of one of the caps. Fig. 6 is a perspective view of one of the hinge members. Fig. 7 is a perspective 40 view of a portion of the body of the clamping member, showing one of the slots for receiving one of the hinge members.

Similar reference characters designate 45 similar parts in the different views.

The clamping member in the preferred 50 form of my invention comprises preferably a body formed from sheet metal into the form of a flattened tube designated by 1 and having curved sides one of which is 55 provided with one or more transverse slots 2, each of which is provided with enlarged end portions 3 and a narrower or contracted intermediate portion 4. In the slots 2 and interlocked with the body 1 are mounted

sheet metal and having a central barrel or eye 5 adapted to receive a pintle 6. Each hinge member is provided with two laterally extending arms 7 fitted in the intermediate portion 4 of one of the slots 2, and 60 provided with enlarged ends or heads 8 respectively fitted in the enlarged portions 3 of said slot. The slots 2 extend transversely across the curved sides of the body 1, so that the end portions 3 and intermediate 65 portion 4 are not located in the same plane. By means of this construction, when the arms 7 are forced into the slots 2 during the process of manufacture, the hinge members will be interlocked with the body 1 so 70 that they can not be accidentally detached therefrom. Pivoted to the pintle 6 is a leaf 9 which is secured to the cover board 10.

The leaf 9, cover board 10, hinge members 5 and body 1 may be covered, in the 75 usual manner, with any suitable binding material, not shown. In order that the sharp ends of the body 1 may not cut or wear the binding material, I preferably provide for the ends of the body caps 11, preferably drawn from sheet metal to a size and shape such that the edges of the caps will respectively abut against the ends of the body 1. The body 1 has each end provided with a plurality of slots 12 into which 80 respectively extend projections 13 which are provided on the adjacent cap 11. The slots 12 and projections 13 are so disposed relatively that lateral movement of the caps relative to the body 1 will not occur. In 85 the drawing I have shown two slots 12 disposed diametrically opposite each other in the curved side walls of the body 1, and two slots disposed respectively in the top and bottom of the body 1 and intermediate of 90 the slots in the side walls. This arrangement of the slots prevents lateral movement of the caps relative to the body. The projections 13 which are mounted in the slots 12 in the top and bottom of the body 1 95 prevent lateral horizontal movement of the caps, while the projections 13 which are located in the slots 12 in the side walls prevent vertical movement of the caps relative to the body 1. The outer ends of the caps 11 100 are rounded at their edges, thereby presenting no sharp edges to cut the binding material. The slots 2 and 12 may be punched in the body 1 while it is in the flat.

I do not limit my invention to the struc- 110

ture shown and described, as many modifications, within the scope of the appended claims, may be made without departing from the spirit of my invention.

5 Having thus described my invention, what I claim and desire to secure by Letters Patent, is:—

1. In a loose leaf binder, a tubular clamping member having in its wall a slot having 10 a contracted portion between its ends, and a hinge member fitted in said slot and interlocking with the clamping member.

2. In a loose leaf binder, a tubular clamping member having a curved wall provided 15 with a slot having a contracted portion between its ends, and a hinge member fitted in said slot and interlocking with the clamping member.

3. In a loose leaf binder, a tubular clamping member having in its wall a slot, and a hinge member having two laterally extending arms fitted in said slot and interlocking with the clamping member.

4. In a loose leaf binder, a tubular clamping member having in its wall a slot having 25 a contracted portion between its ends, and a hinge member having two laterally extending arms fitted in said slot and interlocking with the clamping member.

30 5. In a loose leaf binder, a tubular clamping member having a curved wall provided with a slot having a contracted portion between its ends, and a hinge member having two laterally extending arms fitted in said slot and interlocking with the clamping member.

6. In a loose leaf binder, a tubular clamping member having a curved wall provided 40 with a seat having a contracted portion between its ends, and a hinge member having an eye adapted to receive a pintle, and fitted in said seat and interlocking with the clamping member.

45 7. In a loose leaf binder, a tubular clamping member having a wall provided with a seat having enlarged end portions and a contracted intermediate portion, and a hinge member having portions respectively fitted in said end and intermediate portions, said 50 end and intermediate portions not being located in the same plane.

8. In a loose leaf binder, a tubular clamping member having a wall provided with a seat having enlarged end portions and a nar-

rower intermediate portion, and a sheet 55 metal hinge member having a middle portion formed into a barrel and having two arms fitted in said intermediate portion of the seat the arms having heads respectively fitted in the enlarged end portions of the 60 seat.

9. In a loose leaf binder, a tubular clamping member having a tubular body one end of which is provided with slots, and a cap 65 having projections respectively fitted in said slots, the slots and projections being arranged to prevent lateral movement of the cap and body relative to each other.

10. In a loose leaf binder, a tubular clamping member having a tubular body the ends 70 of which are provided each with slots, and two caps mounted respectively on the ends of the body, each cap having projections fitted respectively in the slots of the adjacent end of the body, said slots and projections being arranged to prevent lateral movement of the caps relative to the body.

11. In a loose leaf binder, a tubular clamping member having a tubular body one end of which is provided at opposite sides of the 80 body with two slots, and a slot intermediate of said two slots, and a cap mounted against said slotted end and having projections respectively fitted in said slots.

12. In a loose leaf binder, a tubular clamping member having a tubular body one end of which is provided at opposite sides of the body with two slots, said end having two slots located respectively at opposite sides of the body intermediate of said first named 90 slots, and a cap mounted against the slotted end of the body and having four projections respectively fitted in said slots.

13. In a loose leaf binder, a clamping member having a tubular body and a cup-shaped hollow cap closing one end thereof and having its outer surface flush with the outer surface of the body, the cap having means for holding it from lateral movement relative to the clamping member. 100

In testimony whereof I have signed my name to this specification in presence of two subscribing witnesses.

WILLIAM P. PITT.
